UNITED STATES PATENT OFFICE.

ELOF NORDSTROM, OF NEWARK, NEW JERSEY, ASSIGNOR TO AMERICAN DAN STOPPER COMPANY, OF BRIDGEPORT, CONNECTICUT, A CORPORATION OF CONNECTICUT.

BOTTLE-CAPPING MACHINE.

1,282,920.

Specification of Letters Patent. Patented Oct. 29, 1918.

Application filed February 9, 1916. Serial No. 77,191.

To all whom it may concern:

Be it known that I, ELOF NORDSTROM, a citizen of the United States, residing at Newark, in the county of Essex and State of New Jersey, have invented certain new and useful Improvements in Bottle-Capping Machines, of which the following is a specification.

This invention relates more especially to
10 bottle-capping machines in which bottles
are automatically fed into position to have
caps applied thereto after which they are
fed into other positions to have said caps
finally secured to the bottles. One of the
15 objects of the present invention is to provide
improved means for feeding bottle caps
from a hopper into which they have been
previously charged. Another object is to
provide improved means for keeping the
20 hopper properly charged so as to avoid any
delay which might be occasioned by the hop-
per becoming exhausted of caps. Toward
the attainment of this object, the present in-
vention contemplates the provision of cap
25 holders which are adapted to be filled in one
place and then transported to the machine
which is to apply them to the bottles. An-
other object is to provide improved means
for moving the cap-holders into and out of
30 position to discharge into the hopper. Other
and further objects will appear in the speci-
fication and be pointed out in the appended
claims, reference being had to the accom-
panying drawings in which.

35 Figure 1 is a front elevation of a machine provided with my improvements, parts being broken away and parts shown in section.

Fig. 2 is a top plan view of the same.

Fig. 3 is a side elevation of the mechanism for operating the cap-holding tubes, parts being shown in section and parts broken away.

Fig. 4 is a fragmentary plan view of some of the driving connections for the same.

45 Fig. 5 is an elevation on an enlarged scale, taken from the left of Fig. 3, parts being broken away and parts shown in section.

Fig. 6 is a detail.

50 Fig. 7 is a combined section and elevation of a hopper and cap feeding mechanism on an enlarged scale, parts being broken away.

Fig. 8 is a combined top plan view and section of the same, parts being omitted.

55 Fig. 9 is an end elevation of Fig. 8, parts

being broken away and parts shown in section.

Fig. 10 is a side elevation of the hopper and parts of the cap-feeding mechanism in its initial position, parts being broken away. 60

Fig. 11 is an end elevation of the same.

Fig. 12 is a view similar to Fig. 10, parts being broken away and the several parts of the cap-feeding mechanism being changed or being shown in different position.

Fig. 13 is an end elevation of the same.

Fig. 14 is a view similar to Fig. 12 showing the parts in an advanced position.

Fig. 15 is an end elevation of the same.

Fig. 16 is a view similar to Figs. 10, 12 and 14, but with the parts in their lowermost positions.

Fig. 17 is an end elevation of the same

Referring more particularly to the drawings, in the embodiment shown therein, the rods 1 serve to mount the frame member 2, said rods 1 being preferably in the form of screws as shown and described in my co-pending application, Ser. No. 48,210, filed August 31, 1915, this construction being useful for raising and lowering the capping 80

101 for raising and lowering the capping mechanism to suit the bottles or other containers of different heights. The standard 3 carries a bracket 4, there being a vertical bearing 5 for the shaft 6 and a horizontal bearing 7 for the shaft 8 which receives its power from the shaft 6 by means of beveled pinion 9 on the shaft 6 which drives the beveled gear 10 on the shaft 8. The shaft 8 carries at its outer end a fly wheel 11. Also keyed to the shaft 8 is a pinion 12 which meshes with a beveled gear 13 and serves to vertically reciprocate the bottle cap clinching device comprising adjacently disposed units 14. This mechanism is fully shown and described in my co-pending application above referred to and need not be specifically referred to herein. The other end of the shaft 8 carries a housing 15 said housing containing a clutch (not shown) which is operated by an arm 16 carried by the upper end of a spindle which carries at its lower end a feeler 17, said feeler being adapted, as

explained in the above mentioned application, to determine the presence or absence of a bottle to be capped. Should there be a failure at any time to present a bottle to the capping mechanism, said feeler serves to operate the clutch mechanism within the housing 15 and to disconnect a sleeve 18 110

which is connected to an eccentric 55, rotating freely on the shaft 8.

As shown in Figs. 1, 2 and 4, a bevel pinion 19 keyed to shaft 8 drives a bevel gear 20 keyed to the upper end of a vertical shaft 21, said shaft being journaled in a bearing 22. The bottom end of said shaft 21 carries a crank arm 23 which is pivotally connected to one end of a connecting rod 24, the other end 10 of said connecting rod being connected by a stud 25 to a lever arm 26, provided with a tangential flange 27 which serves to mount a curved finger 28. As the crank arm 23 moves into the position shown in dotted lines in 15 Fig. 4, the curved finger 28 is thrown into the dotted line position shown in said figure. This movement being adapted to throw one cap holding tube out of discharging position with reference to the hopper to be herein- 20 after referred to, and another holder into discharging position. The lever 26 is journaled upon a vertical shaft 29 which extends upwardly through the table or plate 30, (see Fig. 5) and carries at its upper end a spider 25 31 provided with sockets for receiving a plurality of cap holding tubes. A similar spider 33 is mounted on the shaft 29 adjacent the plate or table 30. Said spiders are each provided with hub portions which are keyed to 30 the shaft 29 by pins 34 as shown in Fig. 7. The lower end of the shaft 29 is provided with a reduced portion 35 journaled in a bearing 36 below the table 30. Any suitable means (not shown on the drawings) may be 35 employed for retaining the tubes 32 in their positions in the spiders 31 and 33. As shown in Fig. 7, each of said tubes 32 is in its turn brought into register with the hopper 37 which depends from the bushing 38 mounted 40 in a hole in the plate 30 (see Fig. 9). Slides 39 are reciprocably mounted on opposite edges of the hopper 37, being retained thereon in the present embodiment by a semi-cylindrical band spring 40 which connects them 45 together and yieldably braces them against the hopper. The lower end of said hopper has mounted on the flat faces thereof, a plurality of yieldable fingers 41 for holding the caps 42 against discharge therefrom. The 50 oscillatable frame is journaled upon oppositely projecting pins 43 carried by the slides 39. Said frame comprises a laterally projecting yoke 44 and downwardly extending arms 45 at either side of the tube 37. Each 55 arm 45 carries a stop 46 which limits the lateral movement of the arm 45 by being brought into engagement with the slides 39. The lower end of the arm 45 is deflected inwardly to constitute a gripper foot 47, which 60 in its upper position is disposed above one of the wings of the bottommost cap in the hopper 37. A pair of pins 48 carried by the swinging end of a lever 49 are disposed above and below the yoke 44. As shown in Fig. 7, 65 the lever 49 is pivoted at one end to a stud 50

adjustably mounted on the lower end of a rod 51 which is threaded into the lug 52 on the machine frame. The connecting rod 53 is pivotally connected at 54 to the lever 49, the upper end of the rod 53 being provided 70 with an eccentric strap running on an eccentric 55 keyed to the sleeve 18. As the rod 53 rises and falls, the parts just mentioned will successively assume the positions shown in Figs. 10 to 17 inclusive. Thus at the end of 75 the up-stroke of rod 53, the arms 45 will be laterally displaced as shown best in Fig. 11, but at the beginning of the down-stroke of the lever 49, the arms will first be thrown into vertical position on the slides 39 so that 80 the grippers 47 will be disposed immediately above the lateral projecting wings of the lowermost cap in the hopper. Secured to each of the arms 45 is a yieldable grip or leaf 56. First the arms 45 move downwardly, the grippers 47 draw the lowermost cap from the hopper by overcoming the resilient pressure of spring fingers 41. At this time the wings of the cap rest upon the leaf spring 56 until the cap rests upon the crown 90 57 of the bottle disposed to receive it (see Figs. 14 and 15). As the downward movement of the arms 45 continues, the grippers 47 force the wings of the cap downwardly into loose engagement with the crown of the 95 bottle, as shown in Figs. 16 and 17. The return stroke of the lever 49 at first moves the arms laterally into the position shown in dotted lines in Fig. 17 and then the continued upward movement of the lever 49 brings 100 the parts to the initial positions shown in Figs. 10, and 11. As shown in Figs. 2 and 5, the table or plate 30 is provided with an upwardly projecting flange 58 against which abuts one end of a spring 59. The other end 105 of said spring abuts against the lever 60 which is pivoted at 61 on the plate 30. The outer end of the lever 60 is adapted to engage the corner of a cap holder 32 so that 110 said holder is retained in register with the hopper during the time that said holder discharges into the hopper. The table 30 is provided with an arcuate slot 62 within which the finger 28 oscillates. Normally this movement of the finger has no effect. When, however, the holder disposed over the hopper, becomes fully discharged, the follower block 63 (see Fig. 7) reaches its lowermost position. Said follower is provided with a deep slot which registers in its lowermost position 115 with a slot 64 in the wall of the tube 32. The lever arm 65 is mounted within the slot in the follower 63 on a pin 66. When the last cap has left the tube, the end of the lever arm 65 is dropped low enough to fall downwardly into the slot 64, an action which brings it in the path of the finger 28 as it oscillates from the slot 62. In consequence, the next movement of said finger in a clockwise direction according to Fig. 2 will en- 120 125 130

gage the lever arm 65 and move the empty holder away from the hopper while at the same time bringing a loaded holder into position to discharge into the hopper. The 5 holders 32 may be filled in any desired or suitable manner. Preferably however, they are filled at a central station and after being properly packed are shipped to various points to be used on machines of the character 10 hereinbefore described for capping bottles. After each bottle receives its cap in the manner already pointed out, it is in the present embodiment passed along to the crimping mechanism where the caps are permanently 15 secured to the bottles.

I claim:

1. In a machine of the character described, means for holding a vessel to be capped, a cap-stacking container disposed above and 20 coaxially arranged with respect to a vessel mounted on said vessel holder, and means reciprocable longitudinally of the common axis of said vessel and cap-stacking container for withdrawing a cap from said container and applying it directly to said vessel.

2. In a machine of the character described, a tubular hopper for caps, a reciprocable slide, and means carried by said slide and movable into and out of position to engage 30 a cap in said hopper to move it from said hopper to the neck of a bottle, said slide carried means being provided with means for releasably engaging the wings of a cap, the reciprocating movement of said slide 35 being sufficiently extended to force said wings close against the neck of a bottle.

3. In a machine of the character described, a hopper tube for caps having laterally extending wings, said tube being adapted to 40 retain the bottom-most cap with its wings projecting, and means for withdrawing the bottom-most cap from said hopper down on to a bottle therebeneath, said cap-withdrawing means including non-yielding fingers 45 movable into position above the projecting wings of said cap before the withdrawal movement of said withdrawing means, and flexible fingers movable into position below said wings before such withdrawal movement.

4. In a machine of the character described, a chute for caps having wings, said chute by its cross section being adapted to accommodate a plurality of superimposed caps 55 with their wings projecting laterally therefrom, an instrumentality provided with means for engaging the wings of a cap to draw said cap from said chute on to a bottle and to bend said wings to lie lengthwise of 60 said bottle, and means for operating said instrumentality.

5. In a machine of the character described, a chute for caps having wings, said chute by its cross section being adapted to accommodate 65 a plurality of superimposed caps with

their wings projecting laterally therefrom, an instrumentality provided with means for engaging the wings of a cap and drawing said cap from said chute on to a bottle, and means for operating said instrumentality, 70 said instrumentality comprising one member which moves to and fro between said chute and the successive bottles presented for capping and another member carried by the first member and movable into and out of 75 position to engage the wings of the bottom-most cap in said hopper.

6. In a machine of the character described, a chute for caps having wings, said chute by its cross section being adapted to accommodate a plurality of superimposed caps with their wings projecting laterally therefrom, an instrumentality provided with means for engaging the wings of a cap and drawing said cap from said chute on to a 80 bottle, and means for operating said instrumentality, said instrumentality comprising a reciprocating slide and means movably mounted on said slide to move into engagement with the wings of the bottom-most cap 85 in said hopper at the beginning of the forward stroke of said slide and to move in an opposite direction at the beginning of the return stroke of said slide.

7. In a machine of the character described, a chute for caps having wings, said chute by its cross section being adapted to accommodate a plurality of superimposed caps with their wings projecting laterally therefrom, an instrumentality provided with 90 means for engaging the wings of a cap and drawing said cap from said chute on to a bottle, and means for operating said instrumentality, said instrumentality comprising a reciprocating slide and means movably mounted on said slide to move into engagement with the wings of the bottom-most cap 95 in said hopper at the beginning of the forward stroke of said slide and to move in an opposite direction at the beginning of the return stroke of said slide, said operating means being connected to said slide by means of the cap engaging means mounted thereon.

8. In a machine of the character described, a chute for caps having wings, said chute by 115 its cross-section being adapted to accommodate a plurality of superimposed caps with their wings projecting laterally therefrom, an instrumentality provided with means for engaging the wings of a cap and drawing 120 said cap from said chute on to a bottle, and means for operating said instrumentality, said instrumentality including a slide reciprocably mounted on said tube, and grippers oscillatably mounted on said slide.

9. In a machine of the character described, a chute for caps having wings, said chute by its cross-section being adapted to accommodate a plurality of superimposed 125 caps with their wings projecting laterally 130

therefrom, an instrumentality provided with means for engaging the wings of a cap and drawing said cap from said chute on to a bottle, and means for operating said instrumentality, said instrumentality including a frame journaled on said slide and provided with inturned ends, said operating means being connected to said frame to oscillate it while at the same time reciprocating said slide.

10. In a machine of the character described, a chute for caps having wings, said chute by its cross-section being adapted to accommodate a plurality of superimposed caps with their wings projecting laterally therefrom, an instrumentality provided with means for engaging the wings of a cap and drawing said cap from said chute on to a bottle, and means for operating said instrumentality, said instrumentality including a frame journaled on said slide and provided with inturned ends, said operating means being connected to said frame to oscillate it while at the same time reciprocating said slide, said hopper being disposed vertically and said frame being provided with yieldable members between which and said inturned ends the wings of a cap are engaged.

11. In a machine of the character described, a chute for caps having wings, said chute by its cross-section being adapted to accommodate a plurality of superimposed caps with their wings projecting laterally therefrom, an instrumentality provided with means for engaging the wings of a cap and drawing said cap from said chute on to a bottle, and means for operating said instrumentality, said instrumentality including a frame journaled on said slide and provided with inturned ends, said operating means being connected to said frame to oscillate it while at the same time reciprocating said slide, said hopper being disposed vertically and said frame being provided with yieldable members between which and said inturned ends the wings of a cap are engaged, and means for driving said operating means to force said projecting ends of the frame downward over the wings of a cap on a bottle.

12. In a machine of the character described, a cap-feeding hopper adapted to hold a pile of caps in predetermined relation, a plurality of cap-holders adapted to

discharge into said hopper, and means for 55 moving said cap-holders successively into position to discharge into said hopper, said moving means including a normally inoperative element which moves into operative position when the last cap leaves a cap- 60 holder.

13. In a machine of the character described, a cap-feeding hopper, a plurality of cap-holders, and means for feeding said cap-holders successively into position to discharge into said hopper, said means including a follower carried by each holder, and a lever arm normally sustained in inoperative position by a portion of said holder, said holder being adapted to release said 70 lever arm when said follower reaches a point adjacent the lower end of the holder.

14. In a machine of the character described, the combination with a hopper, of a tubular holder movable into and out of 75 position to discharge into said hopper, said holder being provided with an opening in a lateral wall thereof, a follower movable within said holder and normally sustained in raised position by caps in said holder, 80 said follower being provided with an element normally sustained in inoperative position by a lateral wall of said holder, and means adapted to engage said element to move said holder away from said hopper, 85 the opening in the lateral wall of said holder being adapted to release said element when the caps are exhausted in said holder.

15. In a machine of the character described, the combination with a hopper, of 90 a holder for caps movable into and out of position to discharge into said hopper, means for moving said holder, and means carried by the holder and movable into position to be engaged by said moving means depending on the presence or absence of caps in 95 said holder.

16. In a machine of the character described, a hopper, a cap-holder movable into and out of position to discharge into said 100 hopper, said cap-holder being provided with normally inoperative means becoming operative when the last cap leaves the holder for moving said cap-holder away from said hopper, and power driven means adapted 105 to engage said normally inoperative means when it becomes operative.

ELOF NORDSTROM.
